Term of patent 14 years

(Cl. D30—1)

FIG. 1.

FIG. 2. FIG. 3. FIG. 4.

FIG. 5.

FIG. 6.

FIG. 7.

FIG. 8.

FIG. 9.

FIG. 10.

FIGURE 1 is a front perspective view of an archery bow draw and release handle showing my new design;

FIGURE 2 is a top plan view of the handle of FIGURE 1;

FIGURE 3 is a front elevational view of the handle of FIGURES 1 and 2;

FIGURE 4 is a rear elevational view of the handle of FIGURES 1-3;

FIGURE 5 is an elevational view of the near end of the handle shown in FIGURE 1;

FIGURE 6 is an elevational view of the end opposite that shown in FIGURE 5;

FIGURE 7 is a top plan view of a slightly modified form of the archery bow draw and release handle showing my new design;

FIGURE 8 is a front elevational view of the modified handle shown in FIGURE 7;

FIGURE 9 is a top plan view of still a different slightly modified form of the handle of FIGURES 1-6; and

FIGURE 10 is a front perspective view of the modification shown in FIGURE 9.

The appearance of the rear of the handle of FIGS. 7 and 9 is the same as that shown in FIG. 4.

I claim:

The ornamental design for an archery bow draw and release handle, substantially as shown and described.
